Primary Examiner — Paula Allen Greene*(74) Attorney, Agent, or Firm* — Skaar Ulbrich Macari, P.A.(57) **CLAIM**

We claim an ornamental design for a headset, as shown and described.

DESCRIPTION

FIG. 1 is a perspective view of a headset showing the claimed design;

FIG. 2 is another perspective view of FIG. 1;

FIG. 3 is a front elevational view of FIG. 1;

FIG. 4 is a rear elevational view of FIG. 1;

FIG. 5 is a left side elevational view of FIG. 1;

FIG. 6 is a right side elevational view of FIG. 1;

FIG. 7 is a top plan view of FIG. 1;

FIG. 8 is a bottom plan view of FIG. 1;

FIG. 9 is an enlarged view of the portion indicated by the square A of FIG. 3; and,

FIG. 10 is an enlarged view of the portion indicated by the circle B of FIG. 8.

The broken lines in the figures represent portions of the article which form no part of the claimed design.

The dot-dash lines in the figures represent the boundaries of the enlarged areas which form no part of the claimed design.

1 Claim, 10 Drawing Sheets# US D836,600 S
